UNITED STATES PATENT OFFICE.

EBEN C. CROCKER, OF BRIDGEPORT, CONNECTICUT, ASSIGNOR OF ONE-HALF TO EDWIN C. HOWE, OF SAME PLACE.

ELECTRIC RAILWAY.

SPECIFICATION forming part of Letters Patent No. 592,528, dated October 26, 1897.

Application filed March 1, 1897. Serial No. 626,636. (No model.)

To all whom it may concern:

Be it known that I, EBEN C. CROCKER, a citizen of the United States, residing at Bridgeport, in the county of Fairfield and State of Connecticut, have invented certain new and useful Improvements in Electric Railways; and I do hereby declare the following to be a full, clear, and exact description of the invention, such as will enable others skilled in the art to which it appertains to make and use the same.

My invention relates to certain new and useful improvements in electric railways, but more particularly has reference to railways which employ a third rail for transmitting the operating-current to the car.

The object of my invention is to provide an exceedingly economical and efficient system for electric railways, and at the same time to observe proper precautions as against danger from the current; and with these ends in view my invention consists in the details of construction and combination of effective parts, such as will hereinafter be particularly set forth, and then specifically designated by the claims.

In the accompanying drawings, which form a part of my application, Figure 1 is an elevation, partly in section, showing a car and road-bed properly constructed and equipped in accordance with my improvement; Fig. 2, a detail broken perspective of the road-bed; Fig. 3, a detail cross-section taken through the third or line rail and the road-bed box, and Fig. 4 a detail broken sectional elevation showing one of the magnets carried by the car.

Similar numbers of reference denote like parts in the several figures of the drawings.

My improvement has nothing whatever to do with any particular kind of motor carried by the car or with any special construction of controller-box and connections between such box and motor, and I have therefore not illustrated such motor, controller-box, and connections, and I will confine my description specifically to the means which I have provided for positively supplying the electric current to the car.

1 is an insulated conduit which extends beneath the road-bed 2 throughout the entire

line, and within this conduit is the live or line wire 3.

4 are boxes, preferably of insulating material, which are sunken in the road-bed. Within each of these boxes is mounted a pair 55 of tubes 5, of any suitable material, wound exteriorly by continuous insulated coils 6, said coils being surmounted and kept in place by rings 7, the lower terminal 8 of said coils being electrically connected with the line-wire 3, while the upper terminal 9 is electrically connected with a contact spring or brush 10, preferably of copper, which latter is within an opening 11 in the top of the box.

12 is an armature which normally rests upon 65 the rings 7 and upon which the spring 10 is mounted, said spring and armature being insulated from each other by the insulating-block 13. Depending from this armature are pins 14, to the lower extremities of which are 70 secured soft-iron cores 15, which latter, in their normal or lowest position, are without the magnetic field of the coils 6.

It will be readily understood that this construction, above described and comprising 75 the tubes 5, coils 6, and cores 15, is in reality a solenoid, the action of which is, of course, to attract the cores 15 when once the latter are elevated within the magnetic field, and in this respect I do not, therefore, wish to be 80 limited to the specific construction of solenoid described, since in this respect there may be considerable variation as to construction without departing from the spirit of my invention.

85 The third-rail system which I employ comprises rails 16 between the car-wheel rails, and these rails 16 rest upon insulated blocks 17 and are separated at their abutting ends by a space sufficient to prevent the jumping 90 of the current from one rail to the other, which space is preferably filled by any suitable insulating material 18. I preferably locate the solenoids above described in pairs, which are near the abutting extremities of these 95 rails, as shown in the drawings, so that there is a pair of these solenoids at each end of a rail; but this arrangement may be departed from, as will be hereinafter explained. These third rails extend immediately above the 100

openings 11 in the boxes, being preferably in actual contact with said boxes, in order to close these openings, so as to keep out dirt, water, or other foreign substances.

5 I have heretofore described that part of my improvement which relates to the road-bed construction, and I will now describe the construction and operation of the devices carried by the car and which coöperate with the parts 10 heretofore described in producing the result aimed at.

I have shown a car similarly equipped at each end with my improvement, and it is therefore deemed necessary to merely state 15 that this is done for the obvious purpose of enabling the motorman to operate the car at either end.

19 20 are levers which are independently pivoted at or about their central portion to a 20 hanger 21 beneath the platform of the car. One end of each lever is normally elevated by means of coil-springs 22 23, which are attached to the body of the car and to said ends, while on the other or normally-depressed extremes 25 of these levers are carried magnets 24 25. These magnets are both alike and one of them is shown in detail at Fig. 4, and it will be observed that there are two windings around the cores of said magnets, the 30 inner coils 26 being connected to any suitable storage battery 27, while the outer coils 28 are connected to at the lower ends to the cores of the magnets, the upper ends of these outer coils being led into the controller-box 29.

35 The operation of my improvement is as follows: Presupposing the car to be at a state of rest and with no current whatever on the third rail, the magnets 24 25 are vitalized from the storage battery 27, which magnets, 40 through the medium of the rails 16, attract the armatures 12 until a good contact is made between the rails and the brush or spring 10. As soon as this contact is made the current from the line-wire 3 will of course be led by 45 the wire 8 up through the coils 28 to the controller-box, and the operation of the latter will now effect the movement of the car. As soon as the connection is made with the line-wire in the manner above described the storage-battery current is automatically switched off in the usual manner, and right in this connection I would say that I have shown no 50 storage battery, since it forms no part of my invention, and, moreover, in the connection in which I use it it constitutes a very ordinary expedient which is merely resorted to in rare instances when for unforeseen reasons the contact is broken between the rails 16 and the line-wire.

60 It will of course be clear that the magnets 24 25 will always be normally in contact with the rails, and that after these magnets are devitalized by switching off the current from the storage battery said magnets will merely 65 perform the function of shoes bearing against the rails, and the contact between the spring

10 and these rails will thereafter be maintained by the influence of the solenoids heretofore described, while at the same time the electric current thereby transmitted from the 70 line-wire through the outer coils 28 will re-vitalize said magnets.

The provision of means for temporarily vitalizing the magnets 24 25 is merely a precautionary measure, since under ordinary circumstances, and especially when the solenoids are located at short intervals beneath the rails 16, the influence of the solenoids will always maintain an electric contact between these rails and the line-wire. It will 80 also be obvious that single solenoids may be located beneath these rails 16 at suitable intervals with practically the same results as are effected by the arrangement shown and described herein, and therefore I do not wish 85 to be limited in this respect.

The separation and insulation of the rails at their abutting ends causes the current to be applied merely to the rails that are occupied by the car, for as fast as the car leaves 90 preceding rails the armatures 12 thereunder will of course fall, while the magnets 24 25, when they come in contact with succeeding rails, will effect the elevation of the armatures thereunder in precisely the same manner hereinbefore set forth. Of course if these rails were in close contact throughout their extent 95 my improvement would operate precisely in the same manner as in the present instance, with the sole exception that the rails remote 100 from the car would be charged with the current, which might prove dangerous to life.

If desired, the magnets 24 25 may carry separate shoes for contact with the rails, and in such instance these shoes will of course be 105 a part of the magnet-cores and will be electrically connected with the coils 28, leading to the controller-box.

It will of course be understood that the outside rails 30 are bonded in the usual manner 110 and that the wheels of the car travel thereon; also any suitable means may be provided and carried by the car for elevating the upper magnets or shoes from the rail when such parts are not in use, and this of course will always 115 be done at one end of said car.

From the foregoing description it will be readily comprehended that I have provided a series of insulated solenoids beneath the insulated rails 16 and have connected the terminals of the coils of these solenoids with the line-wire and with the contacts 10, carried by the armatures, which latter in turn carry the cores of the solenoids, and in this connection it will be clear that the contact-springs 10 are 125 really parts of these armatures, since they are provided merely to afford good contact-points and are insulated from the armatures in order to avoid grounding.

I have shown and described two magnets 130 or shoes 24 25, in order to provide a proper collector to bridge the insulated space between

the rails, so that there may be no break in the current.

Having thus described my invention, what I claim as new, and desire to secure by Letters Patent, is—

1. The combination with a railway system comprising bonded rails and cars capable of traveling thereon each car carrying a suitable motor and controller-box, of a continuous length of insulated rails between the first-mentioned rails laid and secured in position with their abutting ends insulated from each other, magnets carried in pairs at each end of the car and having their cores normally depressed with a spring action against said insulated rails, the coils of said magnets being electrically connected respectively with said cores and controller-box, the insulated line-wire, the insulated solenoids located in the road-bed beneath the insulated rails, the armatures immediately beneath the latter and within the field of said magnets and carrying insulated contacts, and connection between the solenoid-cores and said armatures where-
25 by the elevation of the latter will bring the former within the magnetic field of the solenoids, the coils of said solenoids being electrically connected respectively with said contacts and line-wire, substantially as set forth.

2. The combination of the insulated rails, 30 the car carrying the controller-box and the pivoted levers which in turn carry magnets at their lower diverging ends, springs attached to said car and levers whereby the cores of said magnets are normally depressed against 35 said rails, the insulator-box sunken in the road-bed beneath said rails and having solenoids mounted therein, the insulated line-wire to which the lower ends of the solenoid-coils are electrically connected, the armatures supported by said solenoids within the field of 40 said magnets and carrying insulated contacts with which the upper ends of the solenoid-coils are electrically connected, rigid connec- 45 tions between said armatures and the cores of the solenoids whereby the elevation of the armatures will bring said cores within the magnetic field of the solenoids, and electrical connections between the lower ends of the magnet-coils and the magnet-cores and be- 50 tween the upper ends of said coils and the controller-box, substantially as set forth.

In testimony whereof I affix my signature in presence of two witnesses.

EBEN C. CROCKER.
